(57) **CLAIM**

The ornamental design for a cutter roller, as shown and described.

DESCRIPTION

FIG. 1 is an upper perspective view of a cutter roller including an outer surface with a pattern of docking pins according to our design;

FIG. 2 is a front elevational view of the cutter roller;

FIG. 3 is a rear elevational view of the cutter roller;

FIG. 4 is a left side view of the cutter roller;

FIG. 5 is a right side view of the cutter roller;

FIG. 6 is a top plan view of the cutter roller; and,

FIG. 7 is a bottom plan view of the cutter roller.

The broken lines in FIGS. 1-7 are environmental and form no part of the claimed design of this invention.

1 Claim, 7 Drawing Sheets
